[57] CLAIM

The ornamental design for a studio storage table, as shown and described.

DESCRIPTION

FIG. 1 is a top perspective view of a studio storage table showing our new design;

FIG. 2 is a right side elevational view thereof with the left side being a mirror image thereof;

FIG. 3 is a bottom perspective view thereof;

FIG. 4 is a bottom view thereof;

FIG. 5 is a top view thereof;

FIG. 6 is a top perspective view of a second embodiment of the invention;

FIG. 7 is a right side elevational view thereof with the left side being a mirror image thereof;

FIG. 8 is a bottom perspective view thereof;

FIG. 9 is a bottom view thereof; and,

FIG. 10 is a top view thereof.

The broken line showing of hand hold perforations in FIGS. 1, 2, 3, 6, 7 and 8 is for illustrative purposes only and forms no part of the claimed design.

FIG. 2

FIG. 1

FIG. 3
